UNITED STATES PATENT OFFICE.

FREEMAN PERKINS, OF SEABROOK, NEW HAMPSHIRE.

SHOE AND METHOD OF MAKING THE SAME.

Application filed December 9, 1926 Serial No. 153,562.

The object of this invention is to provide a shoe combining the desirable features of a turn and a McKay-sewed shoe, and is embodied in the improved shoe and the improvements in the method of making it hereinafter described and claimed.

Of the accompanying drawings forming a part of this specification,—

Figure 1 is a side view, showing a last and the upper and outsole of a shoe temporarily secured thereto wrong side out, the outsole being shown by dotted lines.

Figure 2 is a section on line 2—2 of Figure 1.

Figure 3 is a view similar to Figure 1 showing the fore parts of the outsole and upper, stitched together by turn-shoe machine stitches.

Figure 4 is a section on line 4—4 of Figure 3.

Figure 5 is a side view, showing the shoe in the condition shown by Figure 4, removed from the last and still wrong side out.

Figure 6 is a side view, showing the shoe removed from the last and turned right side out.

Figure 7 is a section on line 7—7 of Figure 6.

Figure 8 shows the shoe relasted right side out, the rear parts of the outsole and upper being separated, a shank piece, a toe box, and a counter being shown by dotted lines.

Figure 9 is an enlarged fragmentary longitudinal section through the toe of the shoe and showing the box.

Figure 10 is an enlarged longitudinal section through the heel of the shoe, and showing the counter.

Figure 11 is a side view, showing the shoe removed from the last, and the rear parts of the outsole and upper stitched together by McKay shoe stitches.

Figure 12 is a section on line 12—12 of Figure 11.

Figure 13 is a view similar to Figure 12, showing the channel lip closed.

Figures 14 and 15 are side views, showing opposite sides of the outsole.

Figure 16 is a perspective view of the shank piece.

Figure 17 shows in perspective the box shown by dotted lines in Figures 8 and 11.

The same reference characters indicate the same parts in all of the figures.

In carrying out my invention, I unite an

outsole 20, and an upper 21 with each other, and with a half inner sole 22, as hereinafter described. The outsole is provided in the inner side of its fore part (this being the flesh side of a sole-leather sole) with an internal channel 23, having a closing lip 24. The channel is formed to receive turn-shoe machine stitches 25, and extends from the ball to and around the toe and back to the ball, as shown by Figure 14. The bottom of the channel is separated from the margin of the sole by between substance through which the stitches 25 extend.

The outsole is provided in the outer side of its rear part with external channels 26, having closing lips 27, and extending from the ball to the heel at opposite edges of the shank portion of the sole, as shown by Figure 15. The channels 26 are formed to receive McKay stitches 28, which are covered by the lips 27.

The outsole is first applied wrong side out, to a last 128, as shown by Figures 1 and 2, and secured thereto by a tack 29, as shown by Figure 2. The fore part of the upper is pulled over, to fit it snugly on the fore part of the last, and its margin is temporarily secured to the outsole by lasting tacks 30 as shown by Figures 1 and 2. The fore parts of the upper and sole are then united by the turn-shoe stitches 25, which are formed by a stitching machine of the Goodyear type used in the manufacture of turn-shoes, the stitches 25 being laid in the internal channels 23, and extended through the between substance, as shown by Figures 2 and 4, the lasting tacks being removed, as fast as the stitching operation requires.

The rear parts of the sole and upper are now left unattached to each other, the rear portion of the shoe being open. The shoe is then removed from the last, as shown by Figure 5, and is turned right side out, as shown by Figure 6. The shoe is then relasted right side out, as shown by Figure 8, and the half inner sole 22, the preferred form of which is shown by Figure 16, is placed upon the heel end of the last and marginally overlapped by the edges of the rear part of the upper, as shown by Figure 10, said edges and inner sole being secured to each other by tacks 28. At the same time, the rear part of the upper is pulled over and conformed accurately to the heel end of the last by a bed-lasting machine.

The shoe is then removed from the last,

and the rear parts of the outsole and upper are united to each other and to the inner sole by the McKay shoe stitches 28, as shown by Figure 12, said stitches being laid 5 in the external channels 26, and subsequently covered by the lips 27, as shown by Figure 13.

The shoe is now completed, so far as the union of the outsole, upper, and inner sole 10 is concerned, and may be completed by the usual operations including the attachment of the heel, and the finishing of the bottom and the sole edges.

It will be seen that the described construction of the shoe permits the uniting of the fore parts of the upper and outsole to each other, while the shoe is wrong side out, and the rear parts are unattached, so that the shoe may be easily turned right side out, 20 and the rear part of the upper may be quickly and conveniently pulled over the heel end of the last and fitted closely thereto before the formation of the McKay stitches. The shoe combines the well known advantages 25 of turn and McKay sewed shoes, and is free from the disadvantages of each.

The described method permits the advantageous lining up of the top of the shoe, and the pulling of the usual inner lining 30 and the upper, so that they are smooth and free from wrinkles. When the McKay stitches are formed, there is no strain on the usual shank and heel seams, and the heel seam is straight and accurately located in 35 a central position. The ease of turning the shoe right side out while the rear parts of the sole and upper are unattached, is an important advantage, the distortion, wrinkling, and difficulty attending the turning of a 40 shoe, united all around by turn stitches, being avoided.

Figures 9 and 10 show a leather box-toe 30, incorporated in the toe portion, and a leather heel counter or stiffener 31, incorporated in the heel portion of the upper. The box-toe 30 is molded and placed while 45 in temper, between the inner lining 32 and the outer lining 33, when the shoe is wrong side out, the toe portion of the inner lining being turned back, as shown by Figure 5, 50 and the box placed on the inner lining, rubber or other suitable cement being applied to the opposite sides of the box, and if desired, to the linings. The shoe is turned 55 right side out while the box is in temper. The outer lining 33 is turned back, so that in the completed shoe, the box is confined between the linings, as shown by Figure 9. I find that a leather box incorporated in this 60 way in the toe portion of the shoe, is very durable, and cannot be crushed or damaged by any usage to which the shoe is liable to be subjected.

The counter 31 is interposed between the 65 linings 32 and 33, when the shoe is in the

condition shown by Figure 6, the body of the counter being interposed between and connected to the linings, and the flange of the counter interposed between the margin of the inner lining and the shank piece 22, and 70 secured to the latter, by the tacks 28^a. The counter is thus accurately incorporated and cannot become displaced.

The counter flange is placed next the last, the insole 22 is placed upon the flange, and 75 the edge of the heel portion of the upper is placed upon the insole, as shown by Figure 10, the parts being united by the tacks 28^a.

The McKay stitches are formed between 80 the series of tacks 28^a and the turn shoe stitches 25.

I claim:

1. A shoe comprising an outsole, an upper, a half insole, including a heel portion and 85 a shank portion, and a flanged heel counter, the fore part of the outsole being provided in its inner side with an inner channel extending from the ball at each edge portion to and around the toe, the bottom of said channel being separated from the margin of the sole by between substance, the rear part of the outsole being provided in its outer side with outer channels extending from the ball to the heel, at opposite edge portions, 90 and with lips to close said outer channels, turn-shoe machine stitches securing the fore part of the upper to the fore part of the outsole, and extending through the said between substance, said stitches being formed 95 while the outsole and upper are wrong side out, tacks uniting the heel portion of the upper and the counter flange to the heel portion of the half insole, and driven when the shoe is right side out, and McKay stitches 100 formed when the shoe is right side out and uniting the outsole to the upper and insole between the tack-united portion of the upper and the turn-shoe machine stitches, the McKay stitches being covered by the outer 105 channel flaps.

2. That improvement in the method of making a shoe comprising an outsole, an upper, and a half insole which includes heel and shank portions, said improvement consisting in providing the inner side of the outer sole fore part with an inner channel, extending from the ball at each edge portion to and around the toe, the bottom of the channel being separated from the margin of the sole by between substance, providing the outer side of the outsole with outer channels extending from the ball to the heel at opposite edge portions of the sole, and with lips to close the outer channels, applying the upper and outsole wrong side out to a last, uniting the fore parts of the upper and outsole by turn-shoe machine stitches laid in the inner channel and extending through the between substance, leaving the rear parts 110 115 120 125 130

of the upper and outsole disconnected, removing the upper and outsole from the last and turning them right side out, relasting the shoe, uniting the heel portion of the upper to the heel portion of the half inner sole by tacks, removing the shoe from the last, and uniting the portions of the outsole, upper, and half inner sole between the tack-united portions and the turn-shoe stitches by McKay stitches laid in the outer channels, and covering said stitches by the lips of the outer channels.

3. That improvement in the method of making a shoe, comprising an outsole, an upper, a half insole which includes heel and shank portions, and a flanged heel counter, said improvement consisting in providing the inner side of the outer sole fore part with an inner channel, extending from the ball at each edge portion to and around the toe, the bottom of the channel being separated from the margin of the sole by between substance, providing the outer side of the outsole with outer channels, extending from the ball to the heel at opposite edge portions of the sole, and with lips to

close said channels, applying the upper and outsole wrong side out to a last, uniting the fore parts of the upper and outsole by turn-shoe machine stitches laid in the inner channel, and extending through the between substance, leaving the rear parts of the upper and outsole disconnected, removing the upper and outsole from the last and turning them right side out, relasting the shoe and interposing the counter between the heel portions of the upper and the last with its flange next to the last, applying the half inner sole to the last with its margin between the upper and the counter flange, uniting the heel portion of the upper to the heel portion of the inner sole, and the counter flange by tacks, removing the shoe from the last, and uniting the portions of the outsole, upper, and half insole between the tack-united portions and the turn-shoe stitches by McKay stitches laid in the outer channels, and covering said stitches by the lips of the outer channels.

In testimony whereof I have affixed my signature.

FREEMAN PERKINS.
